EJECTOR FOR CORE DRILLS

William Bernard Barr, Clifton, N. J.

Application March 19, 1946, Serial No. 655,640

4 Claims. (Cl. 125—20)

1

This invention relates to boring instruments, and particularly to tubular boring instruments with cutting means on one end of the tube, and means of ejecting from the tube the part that has been cut by the tube and which is lodged within the tube, and especially for ejecting said part while the tubular member is still rotating.

In the past, tubular cutters have been used and it is customary to provide a spring pressed ejector within the tubular member so that after the tubular boring instrument has cut through a material the spring ejector will force the plug from within the tubular cutter and prepare the cutter for the next cutting operation. However, with such means, in cutting fragile material the ejecting means provides the least amount of force in the initial cutting operation, whereas by the time the final cutting operation is reached the ejecting means will be compressed to provide the greatest force on the remaining skin or surface to be cut. This is detrimental with fragile material in that the ejector may cause sufficient force to break the plug from the material before the cutter has finally cut through same resulting in a ragged broken edge on one side of the material instead of a clean cut. It is also apparent in the known boring instruments that the ejectors used are all formed so that the boring instrument must be stopped in order to permit a manual forcing of the ejecting means to eject the plug that has been cut.

An object of this invention is to provide a tubular boring instrument having means for ejecting the plug formed within the tubular cutter after a cutting operation, and especially means to control the force applied to the plug to be ejected.

Another object of this invention is to provide a tubular boring instrument with manual manipulated means of ejecting the plug formed in such cutting while the boring instrument continues to rotate.

A still further object of this invention is to provide a tubular boring instrument in which the ejecting means may be used while the boring instrument is rotating and in which the amount of force applied to the plug to be ejected is controllable during the cutting operation.

Further objects may be apparent by reference to the following description and the accompanying drawing in which:

Fig. 1 illustrates a cross sectional view of the ejector applied to a tubular boring instrument, and

Fig. 2 illustrates a cross sectional view of the 55

2

ejector, as applied to a tubular drill that is provided with diamond dust cutting means.

Referring to Fig. 1, there is illustrated a tubular boring instrument 10 comprised of a hollow tube 11 having a cutting means at the end 12 and provided on its upper shank with a pair of parallel slots 13, 14 in which a pin 15 is mounted. The pin 15 is also inserted through an ejecting rod 16 which fits loosely within the tube 11 so that it may be reciprocated therein. A collar 17 is affixed to the tube 11 in any manner, such as welding, to be integral therewith and a spring 18 is mounted between the collar 17 and the pin 15 around the external periphery of the tube 11. Thus, the spring 18 normally holds the ejecting rod 16 slightly above the cutting edges 12. A thrust bearing 19 is mounted around the tube 11 above the pin 15 to bear on the pin 15, so that one portion of the bearing will rotate with the pin 15 while the other portion may be grasped by an operator.

Thus, the whole assembly (as illustrated in Fig. 1) may be operated in the following fashion. The shank of the tubular cutter 11 may be mounted in a chuck (not shown) to drive the tubular boring instrument and the cutting end 12 may be applied to the material to be cut. The ejecting rod 16 may be positioned at the cutting level or above the cutting level according to the material to be cut and according to the desired pressure to be applied. To accomplish this, the pin 15 may be passed through any one of a plurality of slots in its upper end. Thus, with the ejecting rod 16 properly set the drill may be operated and as the cutting edge 12 passes through the material, the operator may manually apply a pressure to the thrust bearing 19 or a pivotal arm means may be provided with a fork or other means to apply the desired pressure to the thrust bearing 19. The pressure on thrust bearing 19 will be transmitted to the pin 15 and since the pin is mounted in a pair of slots 13, 14 it may be forced downwardly against the resistance of the spring 18, and moving downwardly will move its lowermost end down against the plug cut by the cutting edges 12 and so the plug may be ejected while the tube 11 is rotating. This permits the operator to quickly move from one boring operation to the next without waiting to stop his drill to remove the plug that has been cut.

Referring to Fig. 2, there is illustrated a similar tubular boring instrument, except that the cutting end is provided with a glass cutting type of bit in which diamond dust cores 20 have been

mounted. In this particular drill used primarily for cutting glass, it is most essential that the ejecting means be withheld from the glass plug so that a force cannot be applied to break the plug from the glass before the cutting means has cut it completely through. In this instance, the ejector may be applied to the glass plug when desired and may be applied during the operation of the drill and will not break the glass plug at any time. It will be noted in Fig. 2 that the ejector cannot place a strain on the glass plug and is entirely under the control of the operator.

It is apparent that ejectors of the type disclosed and illustrated may be applied in any form of tubular cutting means, or circular saws, and provides a controllable ejector that will not interfere with a cutting operation and will provide a desired pressure as applied by the operator. Many ramifications and changes may be made without departing from the spirit of this invention and this invention shall be limited only by the appended claims.

What is claimed is:

1. A boring instrument including a shank part provided with an axial bore, a tubular cutter affixed to the hollow end of said shank, an ejecting rod slideable in the axial bore, two parallel slots in the shank at the upper end of the axial bore, a pin passed through said parallel slots and said ejecting rod at its upper end to slidably hold said ejector within the axial bore, resilient means mounted between said pin and the lower end of said shank to hold said ejector in a retracted position, and rotatable means mounted around said shank to bear on said pin to operate said ejecting means.

2. A boring instrument including a shank part provided with an axial bore, a tubular cutter having diamond dust bonded pins mounted in the cutting end thereof, an ejecting rod slideably mounted in the axial bore, two parallel slots in the shank at the upper end of the axial bore, a

pin passed through said parallel slots and said ejecting rod at its upper end to slidably hold said ejector within the axial bore, resilient means mounted between said pin and diamond dust cutting means at the lower end of said shank to hold said ejector in a retracted position, and rotatable means mounted around said shank to bear on said pin to operate said ejecting means.

3. A drilling tool including a stem formed tubular at one end and provided with a cutting edge, a rod slidably mounted in said tubular end, said tubular shank of said stem having a pair of parallel axially extending slots formed therein, a pin projecting diametrically outwardly from the periphery of said rod and engaging in said slots, a cutting means carried on the end of said tubular member, resilient means mounted between said pin and the cutting end of said tubular stem to retain said rod within the tubular stem, a bearing embracing said stem and resting on the diametrically positioned pin, means to apply a force to the ejecting rod to eject the material cut during the rotation of the tubular cutter.

4. A drilling tool including a stem formed tubular at one end and provided with a cutting edge, a rod slidably mounted in said tubular end, said tubular shank of said stem having a pair of parallel axially extending slots formed therein, a pin projecting diametrically outwardly from the periphery of said rod and engaging in said slots, said pin extending beyond the periphery of said stem to support a bearing thereon, a cutting means carried on the end of said tubular member, resilient means mounted between said pin and the cutting end of said tubular stem to retain said rod within the tubular stem, said bearing embracing said stem and resting on the diametrically positioned pin, means to apply a predetermined force to the ejecting rod to eject the material cut during the rotation of the tubular cutter.

WILLIAM BERNARD BARR.
